THREAD TAKE-UP FOR SEWING MACHINES

Paul Kuhlig, Kenmore, N. Y., assignor to Consolidated Packaging Machinery Corp., Buffalo, N. Y., a corporation of New York

Application December 9, 1932, Serial No. 646,436

4 Claims. (Cl. 112—249)

This invention relates to a thread take-up for sewing machines and is shown as embodied in a sewing machine which sews an interlocking two thread chain stitch, although the present invention can be used in connection with any type of sewing machine where it is desirable to take up the slack in the thread resulting from the reciprocation of the needle and to restrict the size of the loop formed by the needle so that, when running at very high speeds this loop is always caught by the looper and the stitch always completed.

One of the principal objects of the present invention is to provide a thread take-up between the tension adjusting device and the reciprocating needle holder of a sewing machine which take-up device engages and releases the thread being fed to the needle holder as the needle holder reciprocates and in so engaging the thread moves the thread in such manner as to take up all slack in this thread resulting from the reciprocation of the needle holder in sewing; draws the loop made by the needle to a small size so that it is always caught by the looper and is never lost; allows a small amount of slack at the start of the forward stroke of the needle holder so as to provide adequate thread for the formation of the loop; and on the retraction of the needle holder pulls upon the thread so as to tighten the stitch.

A further object of the present invention is to provide such a take-up device which is readily adjustable to provide the exact size of loop desired, this being effected by adjustably moving the take-up device toward and from the work being operated upon.

A further purpose of the present invention is to provide such a thread take-up which is extremely simple in construction, can be readily adjusted and which, under all conditions of operation, particularly at very high speeds of the sewing machine, takes up and feeds out the slack in the needle thread each time the needle is reciprocated toward and from the material being sewn, thereby avoiding all danger of breaking or snarling the thread as well as restricting the size of the loop so as to always be caught by the looper and drawing upon the needle thread when the stitch is completed so as to tighten the stitch.

Another purpose is to provide such a device which is extremely compact and inexpensive and which is fitted in place of the usual thread guide or eye of a standard machine, thereby enabling the take-up device to be applied to standard machines as now constructed by removing the thread guide and substituting the present take-up.

In the accompanying drawings:

Fig. 1 is a front elevation of a sewing machine equipped with my thread take-up.

Fig. 2 is an end elevation of the same.

Fig. 3 is a horizontal fragmentary section taken on line 3—3, Fig. 1.

Fig. 4 is a perspective view of the thread take-up embodying the present invention and detached from the sewing machine.

Figs. 5-10 are fragmentary horizontal sections similar to Fig. 3 and showing progressively the 10 operation of the take-up as the needle is reciprocated back and forth in sewing a double thread interlocking chain stitch.

The take-up forming the subject of the present invention is designed primarily for use in a sewing machine in which the needle is carried by a needle holder and is reciprocated through the material being sewn, the needle, on being projected forwardly, entering the triangle formed between a previously formed loop and the looper 20 thread, and on retracting forming a loop which is caught by the looper and held until the needle is again reciprocated forwardly. In operating such machines at high speeds, and particularly with twine the loop formed by the needle while 25 retracting tends either to form on both sides of the needle, or if formed on only one side of the needle, is excessively large so that it frequently drops down, is not caught by the looper and a failure in stitching results. Moreover, in machines 30 operating at high speeds without a take-up device there is a tendency for the needle thread to be broken and snarl and no adequate provision is made for drawing the stitch tight after it is formed. The present take-up is designed to 35 overcome these difficulties and in its general organization consists of a stationary cam plate around which the needle thread between the tension adjusting device and the needle holder is drawn back and forth as the needle holder re- 40 ciprocates, this cam plate being so designed that as the needle holder reciprocates back and forth a loop or lateral deflection is formed in the thread and then paid out, thereby taking up the slack in 45 the thread. The cam plate is also so shaped that it adjustably imposes tension upon the needle thread as the needle holder retracts, thereby decreasing the normal size of the loop formed by the needle and insuring its being reliably caught 50 by the looper. This tension is continued so as to draw the stitch tight and at the end of the retraction movement of the needle the thread is released by the cam plate so as to provide a limited slack in the thread and thereby provide 55

enough thread for the proper formation of the next succeeding loop.

The sewing machine in connection with which my invention can be used, can be of any usual and well known form, that shown in the accompanying drawings being a sewing machine which sews a chain stitch with an interlocking thread. The sewing machine is adapted for sewing any kind of material but is particularly adapted for 10 sewing at high speeds and for sewing with twine or other relatively coarse sewing materials.

Inasmuch as the general features of the sewing machine shown in the accompanying drawings are old and well known, a detailed description is deemed unnecessary except as affecting the take-up device forming the subject of the present invention. The operating parts of the sewing machine are shown as carried by a stationary frame 12 carrying a horizontal crank shaft 13 which is driven by a pulley 14, this crank shaft having the usual fly wheel 15. The end of the crank shaft 13 adjacent the needle is formed to provide a crank 16 which reciprocates a connecting rod 17, the lower end of which is connected to one arm 18 of a bell crank lever 19. This bell crank lever is pivoted, as at 20, to the machine frame 12 and its other arm 21 is connected by a link 22 with the horizontal reciprocating rod or needle holder 23 which carries the needle 24. The needle 24 is removably secured to the end of the reciprocating rod or needle holder 23 in any usual and well known manner and the rod 23 is guided for horizontal reciprocating movement in a pair of slideways 25 and 26. Each 35 of these slideways is suitably mounted on the machine frame 12 and carries an eye 27, which receives the needle thread 28. This needle thread is fed from a suitable spool (not shown) through a tension adjusting device 29 and through a tubular guide 30, the lower end of which is disposed immediately above the axis of the reciprocating needle rod 23. From the lower end of the tubular guide 30 the thread 28 passes through an eye 31 in the rear end of the reciprocating 40 needle rod 23, thence through the eyes 27 and thence through the eye in the point of the needle.

It is apparent that, in the absence of provision to prevent it, each time the needle rod 23 is retracted, slack would occur in the thread 28, the 50 present invention being designed to take up this slack as hereinafter explained. It is also apparent that in the absence of provision to prevent it there is nothing definitely limiting the size or form of the loop formed by the needle, this 55 being generally determined only by the amount of thread withdrawn from the tension device at the end of the return stroke of the needle holder. Moreover, it is also apparent that there is nothing other than the resistance of the tension adjusting 60 device for tightening the stitch after it has been made.

The sewing machine is provided with the usual presser foot 32 which is yieldingly held against the side of the material being stitched by a spring 65 33. The sewing machine is also provided with the usual thread cut off which is driven from the pulley 35 on the crank shaft 13 by means of a belt 36 which passes around another pulley 37.

The looper 38 is carried at one end of a horizontal arm 39 which is fixedly clamped to the lower end of a connecting rod 40. The upper end 70 of this connecting rod 40 is secured to the crank 41 on the crank shaft 13 and the connecting rod is guided, intermediate its ends, by a pivoted block 42, this block being pivoted, as at 43, so

that it is free to turn about a horizontal axis, lengthwise of the crank shaft 13. As an auxiliary means for turning the block and avoiding wear between the connecting rod 40 and the swinging block 42, a leaf spring is also preferably secured 5 to the side of the connecting rod 40 and bears against one side of the block 42. The thread 44 to the looper can be fed in any suitable manner. The mounting of the looper 38 in this manner gives the required vertical movement to enter 10 the loop formed by the backward movement of the needle and also gives it the necessary horizontal movement for drawing this loop along the stitch line and for forming the triangle which is entered by the needle on the next succeeding forward stroke.

The sewing machine shown, is provided with the usual feed mechanism which consists of a feed dog (not shown) which is carried at the lower end of a vertical lever 54. This vertical lever 54 20 is pivoted at its center, as indicated at 55, so that it has both lateral and fore and aft movement and at its top this lever 54 is guided in its movement by an eccentric 56 and a cam block 59 having a cam groove 57. The eccentric 56 and the 25 groove 57 in the same block 59 are designed to give the feed dog (not shown) the required movement to advance the material a step after each stitch and then retract away from the material and to its original position for its next succeeding operative stroke.

The rear end of the reciprocating needle holder or rod 23 is arranged in a tubular extension 45 which is suitably secured at one end to the machine frame 12 and projects outwardly therefrom. 35 The front side of this tubular extension 45 is provided with a slot 46 in which the eye 31 on the reciprocating needle holder 23 travels. On this tubular extension 45 is mounted the thread take-up plate forming the subject of this invention, 40 which, as best shown in Fig. 4, comprises a metal plate 47 having a rounded rear portion 48 which fits over the top of the tubular extension 45 and a cam extension 49 which projects forwardly and is horizontally disposed. The plate 47 is secured 45 to the tubular extension 45 by a screw 50, this screw passing through a slot 51 in the take-up plate 47 so as to permit of the adjustment of the take-up plate along the tubular extension 45. The cam extension 49 of the thread take-up plate is 50 designed to permit a limited amount of slack in the thread at the start of the forward reciprocation of the needle, this amount of slack being necessary for the formation of a loop by the needle. It is also so designed that as the needle 55 holder reciprocates it takes up the slack in the needle thread and pays it out as required, thereby avoiding breaking of the thread. It is also so designed that on the retraction of the needle holder, a slight tension is imposed upon the needle 60 thread so as to decrease the size of the loop formed by the needle and insure its being properly caught by the looper. This cam plate also imposes additional tension on the needle thread as the needle holder continues to retract so as to draw the stitch 65 tight. To accomplish these purposes the cam plate 47 can be of various forms, but as shown in the drawings, has a substantially circular salient cam portion 52 on the side nearest the needle and terminates in a receding cam portion 53 on 70 the side remote from the needle.

In Figs. 5-10, inclusive, is illustrated the action of the cam extension 49 as the needle and its holder are reciprocated back and forth in sewing.

In Fig. 5 the needle 24 and needle holder 23 are shown in their fully retracted positions, that portion of the needle thread between the eye 31 and the tubular guide 30 being wholly free from the cam extension 49. The cam 49 does not engage the needle thread until the needle holder has moved forward a short distance and it is therefore apparent that this distance of movement provides a limited slack in the thread, which slack is necessary for the subsequent formation of a loop by the needle.

Fig. 6 shows the next successive position of the needle and needle holder, the needle having entered the material and having entered the triangle of thread held by the looper, the upper leg of this triangle comprising a loop previously formed by the needle and held by the looper and the lower leg of this triangle comprising the looper thread 44. During this movement, the length of the needle thread between the eye 31 on the needle holder 23 and the outlet end of the tubular guide 30 is caught by the receding end 53 of the cam groove 49 and as the needle moves forwardly this length of thread travels along this receding portion of the cam and is deflected laterally outward onto the salient portion thereof.

Fig. 7 shows a next succeeding position of the needle and needle holder in its forward movement. In this position the length of thread between the eye 31 on the needle holder and the outlet end of the tubular guide 30 is caught by the cam plate in the position shown.

As the needle reaches its fully projected position, shown in Fig. 8, the cam plate 49 is so positioned along the tubular support 45 that the length of thread between the eye 31 on the needle holder and the outlet end of the tubular guide 30 slips around the rounding salient face 52 of the cam and rides down to the base of the cam adjacent the tubular support 45, this portion of the cam being substantially circular for this purpose.

In Fig. 9 is illustrated the start of the returning movement of the needle and needle holder from their fully projected positions. As the needle and needle holder return the needle thread is held at the base of the salient portion 52 of the cam adjacent the tubular support 45 and a tension is thereby imposed upon the needle thread so as to draw upon the loop being formed by the needle in so retracting and limiting its size. This prevents the formation of an excessively large loop by the needle in retracting, which large sized loop, during high speed sewing, is liable to drop down and not be caught by the looper 38, thereby causing the sewing machine to drop a stitch.

As the needle and needle holder move back further the slack in the thread is continued to be taken up by the cam 49 and this cam imposes an increasing tension upon the needle thread so that the stitch just formed is drawn tightly into the material being stitched. When this tension increases to the point where the thread will no longer be retained on the nose of the cam the length of thread between the outlet end of the tubular guide 30 and the eye 31 on the needle holder slips around the salient face of the cam to the receding part 53 thereof, as best shown in Fig. 10. During the final retracting movement of the needle holder the thread is drawn free from the cam plate 49 to the starting position illustrated in Fig. 5. During this last part of the return movement of the needle holder and needle additional thread is drawn through the tension device 29 for forming the next succeeding stitch.

From the foregoing it is apparent that the

take-up plate shown in Fig. 4 comprises a very simple, efficient and reliable means for taking up the slack in the needle thread of the sewing machine as the needle and its holder are reciprocated back and forth during the sewing operation. The take-up plate also insures the provision of the requisite amount of slack for the formation of a small sized loop and positively prevents the formation of an excessively large loop during high speed operation of the machine, such excessively large loops being in danger of not being properly caught by the looper. The take-up plate, as shown, also insures that the stitch is drawn tight, thereby providing firmer and tighter sewing. It is also apparent that the take-up plate can be easily applied to standard machines now in use without difficulty, the present take up plate supplanting an eye mounted on the tubular extension 45 in standard machines as now made.

I claim as my invention:

1. A thread take-up for a heavy duty sewing machine for sewing twine and coarse thread having a reciprocating needle holder arranged parallel with the main shaft and carrying a needle at one end and having a single thread guide mounted at its other end, a tension adjusting device feeding the thread to said thread guide and means for reciprocating said needle holder, comprising a stationary cam arranged between said thread guide and tension adjusting device and projecting laterally of said needle holder into the path of the length of thread between said tension adjusting device and said needle holder guide, said cam being formed to provide a salient portion, said salient portion moving said length of thread laterally of said needle holder to form and retain a loop in said length of thread each time the needle holder is moved toward and from its extreme retracted position, said salient portion releasing said thread each time the needle holder is fully retracted, the loop formed and held by said cam taking up the slack in said length of thread as said needle holder is reciprocated.

2. A thread take-up for a heavy duty sewing machine for sewing twine and coarse thread having a reciprocating needle holder arranged parallel with the main shaft and carrying a needle at one end and having a single thread guide mounted at its other end, a tension adjusting device feeding the thread to said thread guide and means for reciprocating said needle holder, comprising a stationary cam arranged adjacent to and to one side of said thread guide and projecting laterally of said needle holder into the path of the length of thread between said tension adjusting device and said needle holder guide, said cam being formed to provide a salient portion on that side adjacent said needle and a receding portion on that side remote from said needle, said cam moving said length of thread laterally of said needle holder to form a loop in said length of thread each time the needle holder is reciprocated from one extreme position to the other and the end portion of said cam adjacent said needle being adapted to hold said loop during a part of the retracting movement of said needle holder and the opposite end of said cam being adapted to release said loop in the fully retracted position of said needle holder.

3. A thread take-up for a heavy duty sewing machine for sewing twine and coarse thread having a reciprocating needle holder arranged parallel with the main shaft and carrying a needle

at one end and having a single thread guide mounted at its other end, a tension adjusting device feeding the thread to said thread guide and means for reciprocating said needle holder; 5 comprising a stationary cam arranged adjacent to and to one side of said thread guide and projecting laterally of said needle holder into the path of the length of thread between said tension adjusting device and said needle holder 10 guide, said cam being formed to provide a substantially circular salient portion on that side adjacent said needle and a receding portion on that side remote from said needle, said cam moving said length of thread laterally of said needle holder to form a loop in said length of thread each time the needle holder is reciprocated from one extreme position to the other and the end portion of said cam adjacent said needle being adapted to hold said loop during a part of the 20 retraction movement of said needle holder and the opposite end of said cam being adapted to release said loop in the fully retracted position of said needle holder.

4. A thread take-up for a heavy duty sewing machine for sewing twine and coarse thread having

5 ing a reciprocating needle holder arranged parallel with the main shaft and carrying a needle at one end and carrying a single movable thread guide which is located at its opposite end, a pair of stationary thread guides between said movable thread guide and the needle, a tension adjusting device for feeding the thread to said movable thread guide, stationary thread guides and needle and a third stationary thread guide guiding the stretch of thread between said tension 10 adjusting device and said movable thread guide; comprising a stationary cam engaging the stretch of thread between said third stationary thread guide and said movable thread guide, said cam being formed to provide a salient portion, said 15 salient portion moving said stretch of thread laterally of said needle holder to form and retain a loop in said stretch each time the needle holder is moved toward and from its extreme retracted position, said salient portion releasing said 20 stretch each time the needle holder is fully retracted, the loop formed and held by said cam taking up the slack in said stretch of thread as the needle holder is reciprocated.

PAUL KUHLIG. 25
